UNITED STATES PATENT OFFICE.

ALFRED C. SMITH, OF NEW YORK, N. Y.

DEVICE FOR EXHIBITING MAGNETIC AND NON-MAGNETIC WATCH-MOVEMENTS.

SPECIFICATION forming part of Letters Patent No. 393,402, dated November 27, 1888.

Application filed September 7, 1888. Serial No. 284,825. (No model.)

To all whom it may concern:

Be it known that I, ALFRED C. SMITH, a citizen of the United States, residing at New York, in the county of New York and State 5 of New York, have invented certain new and useful Improvements in Devices for Exhibiting Magnetic and Non-Magnetic Watch-Movements; and I do hereby declare the following to be a full, clear, and exact description of the 10 invention, such as will enable others skilled in the art to which it appertains to make and use the same.

My invention relates generally to mechanical exhibits for demonstrating the comparative 15 properties and actions of the elements of magnetic and non-magnetic watch-movements when arranged in a magnetic field or under the influence of a magnet, and it relates particularly to exhibiting devices of this character 20 for demonstrating the effect of magnetism on balance-wheels and hair-springs made from different alloys or from different metals and alloys; and it consists in the improved construction and combinations or arrangements 25 of parts, hereinafter fully disclosed in the description, drawings, and claims.

The objects of my invention are, first, to provide mechanical exhibits for retail watch-dealers for enabling them to practically demonstrate 30 to customers the effects of magnetism upon watches containing magnetic and non-magnetic elements in their movements, and to also enable them to avoid the objectionable result hitherto obtaining of magnetizing magnetic watches in testing or comparing the same 35 with non-magnetic watches while demonstrating or explaining their differences; second, to provide a suitable support or base-plate upon which said magnetic and non-magnetic elements 40 may be mounted and brought into a magnetic field or under the influence of a horseshoe or other suitable magnet; and, third, to provide a suitable box or casing for covering, protecting, and displaying said elements.

45 In exhibiting or comparing the properties and actions of magnetic and non-magnetic watch-movements as hitherto practiced the magnetic movement becomes magnetized, and consequently seriously injured or useless, thus 50 rendering such exhibition or comparison expensive and otherwise objectionable. Hence, as stated, for the purpose of enabling retail watch-dealers to intelligently exhibit and ex-

plain the differences in action and properties between a magnetic and a non-magnetic watch-movement under the influence of the poles of a magnet, I have constructed a device in which one or more magnetic balance-wheels and hair-springs, made, for instance, of steel or steel and brass, and a balance-wheel and hair-spring 60 made of a suitable non-magnetic alloy may be exhibited and explained by being set in motion and subjected to magnetic influence, thus effecting a practical demonstration of the comparative affections of the actions of said balance-wheels and hair-springs as made of the 65 respective metals named.

My device is illustrated in the accompanying drawings, forming part of this specification, in which the same reference-numerals indicate the same parts, and in which—

Figure 1 represents a top plan view of a disk-shaped support or base plate with the bridges, the balance-wheels, and the hair-springs secured thereto, an ordinary horseshoe-magnet being also represented with its poles adjacent thereto; Fig. 2, a top plan view of a box or casing having a metallic back plate and periphery and a glass front with my device enclosed therein, an ordinary horseshoe-magnet 75 being also represented in proximity thereto; and Fig. 3, a section of the same on the line *x x* of Fig. 2, the magnet being omitted.

In the drawings, the numeral 1 indicates a brass support or base-plate, which is preferably made in disk form; 2, the wall or periphery projecting upwardly therefrom, and 3 the glass top or front, these parts constituting a suitable box or casing for protecting and displaying or demonstrating with my exhibiting 85 device. Two or more bridges, 4 and 5, are secured to said base-plate; also, balance-wheels 6 and 7 are pivoted between the free ends of said bridges and base-plate, and hair-springs 8 and 9 are secured in place in the usual or any 90 suitable manner.

The balance-wheel 6 and hair spring 8 are made of non-magnetic alloys—that is, alloys which will not be attracted or affected by magnetism or electricity—while the balance-wheel 100 7 and hair-spring 9 are made of magnetic metals, such as steel or steel and brass. When said balance-wheels and hair-springs are set in motion by giving the base-plate or casing a sudden reciprocation or vibration with the 105 hand and the magnet 10 is brought near them,

the balance-wheel and hair-spring which are made of the non-magnetic alloy or alloys will continue to vibrate and will not be affected by the magnet, while the balance-wheel and hair-spring which are made of magnetic metal or metals will be quickly retarded and stopped by the magnet, and thus the comparative effect of the magnetic attraction for these parts can be readily demonstrated and understood; also, it is found in practice that when both the balance-wheels and hair-springs are at rest or not vibrated the magnet, when applied, will attract, start, and move the balance-wheel and hair-spring which are made of magnetic metals, while it will have no effect whatever upon the balance-wheel and hair-spring made of non-magnetic alloy or alloys. By means of this simple device the differences between and the advantages of the non-magnetic elements of watch-movements over those which are magnetic, when arranged in a magnetic field or in proximity to a magnet, may be easily demonstrated, and this without stopping, seriously affecting, or rendering useless an entire magnetic movement, as has generally been the result heretofore.

In my former invention, as disclosed in the patent granted to me February 21, 1888, No. 378,339, the display-stands for non-magnetic watches and watch-movements are designed to attract attention to the latter and show their non-magnetic properties while running in proximity to the poles of the magnets arranged upon said stands, which are displayed in the windows of jewelry stores, while my present device is intended to enable retail jewelers to practically and distinctly demonstrate to customers the difference in effect of magnetism upon some of the elements of magnetic and non-magnetic watch-movements; also, in my former invention provision was only made for testing or comparing the effect and non-effect of magnetism upon complete watches or watch-movements, which in course of time seriously affected such movements as were made of magnetic metals and finally rendered them useless, whereas in my present invention I only employ portions of entire magnetic and non-magnetic watch-movements, and thus avoid the necessity of injuring or destroying the whole of magnetic movements and at the same time simplify and cheapen my former construction.

I do not restrict myself to the employment of any particular construction of magnetic or non-magnetic balance-wheels and hair-springs, as any of the various forms now existing may be supported upon the base plate 1 and used for demonstrating the effect and non-effect of magnetism thereon; also, the box or casing may be dispensed with and only the support or base-plate used in demonstrating, and other minor changes may be made in the construction and arrangements of the parts of my device without departing from the spirit of my invention.

Having thus fully described the construction and combination or arrangement of the several parts of my exhibiting device, its operation and advantages, what I claim as new is—

1. In a device for exhibiting the effect and non-effect of magnetism upon the elements of magnetic and non-magnetic watch-movements, the combination of a support or base-plate, 75 magnetic and non-magnetic watch-movement elements mounted upon said support or base-plate, and a magnet which, on being alternately placed in proximity to said elements, will demonstrate their magnetic and non-magnetic 80 properties, substantially as and for the purpose described.

2. In a device for exhibiting the effect and non effect of magnetism upon the elements of magnetic and non-magnetic watch-movements, 85 the combination of a support or base plate, a magnetic balance-wheel and hair-spring and a non-magnetic balance-wheel and hair spring mounted upon said support or base-plate, and a magnet which, on being alternately placed 90 in proximity to said balance-wheels and hair-springs, will demonstrate their magnetic and non-magnetic properties, substantially as and for the purpose described.

3. In a device for exhibiting the effect and 95 non effect of magnetism upon the elements of magnetic and non-magnetic watch-movements, the combination of a support or base-plate, bridges mounted thereon, a magnetic balance-wheel and hair-spring and a non-magnetic 100 balance-wheel and hair spring secured to said base-plate and bridges, and a magnet which, on being alternately placed in proximity to said balance-wheels and hair-springs, will demonstrate their magnetic and non-magnetic 105 properties, substantially as and for the purpose described.

4. In a device for exhibiting the effect and non-effect of magnetism upon the elements of magnetic or non-magnetic watch-movements, 110 the combination of the bridges, the magnetic and non-magnetic balance-wheels and hair-springs, and a suitable box or casing for covering, supporting, and protecting said parts, substantially as described.

5. In a device for exhibiting the effect and non-effect of magnetism upon the elements of magnetic or non-magnetic watch-movements, the combination of a support or base-plate, the bridges mounted thereon, the magnetic and 115 non-magnetic balance-wheels and hair-springs pivoted and secured between said bridges and base-plate, and a box or casing for inclosing and protecting said parts, which is provided with a glass top, substantially as described.

In testimony whereof I affix my signature in presence of two witnesses.

ALFRED C. SMITH.
